VARIABLE-WIDTH PRESSER-FOOT MECHANISM.

Application filed April 19, 1916, Serial No. 92,141. Renewed February 27, 1922. Serial No. 539,772

This invention relates to sewing machines adapted especially for shop and factory practice, and has particular reference to machines of the two needle type employed for sewing lace, insertion, braid, or the like upon cloth by a single operation.

Among the objects of the present invention is to provide for a two needle sewing machine, a presser foot adjustable laterally along with the varying of the space between the needles to accommodate lace of varying widths.

Another object of the invention is to provide an adjustable presser foot having lace feeding devices associated therewith, the feeding devices as well as the presser foot being of variable width in accordance with the width of the lace being sewed. By the term lace as used herein, I mean to cover any analogous trimming material.

A still further object of the invention is to provide presser foot mechanism for lace sewing machines including two relatively laterally movable main parts, lace feeding means adjustable therewith to accommodate varying widths of lace, and cutting devices for trimming out the cloth beneath the lace and closely adjacent the two lines of stitches.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which

Figure 1 is a side elevation of one embodiment of the invention, parts being in vertical section;

Figure 2 is a vertical transverse section on the broken line 2—2 of Figure 1;

Figure 3 is a horizontal section on the line 3—3 of Figure 1;

Figure 4 is a view similar to Figure 1, but indicating other features of construction;

Figure 5 is a front elevation of the parts shown in Figure 4, the throat plates being in vertical section on the line 5—5 of Figure 4;

Figure 6 is a vertical sectional detail on the line 6—6 of Figure 5;

Figure 7 is a view of the same with 55 changed position of some of the parts;

Figure 8 is a vertical section on the line 8—8 of Figure 5;

Figure 9 is a view of the same with the 60 parts in different position;

Figure 10 is a front elevation of the lace feeding bar and attachments;

Figure 11 is a sectional view looking 65 downwardly from the inclined plane indicated by the line 11—11 of Figure 4;

Figure 12 is a fragmentary transverse section approximately on the line 12—12 of Figure 4;

Figure 13 is a vertical transverse section 70 on approximately the plane of the needles and showing the needle bar and needle controlling devices in elevation; and

Figure 14 is a partial plan view and partial horizontal section indicating the means 75 for adjusting the needle holders laterally in accordance with the lateral adjustment of the presser foot, and lace feeding and cloth cutting devices.

Referring now more particularly to Figures 1 to 3, I show a presser foot 15 comprising right and left halves or parts 15^a and 15^b movable laterally toward and from each other and both movable relatively to the presser foot bar 16 carried in any well known manner by the sewing machine head. 80

The bottom of the presser foot is provided with a transverse slot 17 in the remote ends of which the needles 18 and 19 are adapted to reciprocate with the needle bar 20 of any suitable type, but preferably of the type shown in detail and claimed in my pending application for variable width two needle sewing machines, filed of even date herewith, Serial No. 92,140 (patented August 5, 1924, #1,503,921). The two parts 90 of the presser foot are substantially duplicates, except that one is right and the other is left and hence the slot 17 is formed in both parts as shown in Figures 2 and 3. The effective length of the slot, according to 95 the lateral adjustment of the presser foot parts, corresponds with the width of the lace being used so that the edges or selvage of the lace will be engaged by the needles.

In Figures 4 and 5 I show a vertical reciprocating lace feeding bar 21 having laterally adjustable right and left parts 21^a and 21^b, each part carrying a series of fin-

gers 22 at its lower end acting downwardly and rearwardly along a lace feeding table 23 inclined toward the points of the needles at an inclination of about forty-five degrees.

5 The bar 21 is adapted to be reciprocated in a vertical plane in front of and parallel to the needle bar by any suitable mechanism not shown herein. The lower end of the bar 21 is shown provided with oppositely 10 projecting lateral lugs 24 extending into vertical slots 25 formed in the side wings 26 at the front part of the presser foot or just above the lace table 23. The plane of the bar 21 intersects the middle portion of 15 the inclined table 23 and the fingers 22 extend downwardly and rearwardly to points approaching the lower edge of the table, or close to the lace slot 17. The fingers are held forwardly and downwardly toward or 20 against the table by means of leaf springs 27. The wings 26 being substantially stationary except as they move coincidentally with the slight movement of the presser foot, and the slots 25 being vertical, the 25 lower portion of the lace bar is maintained substantially in a vertical plane during its reciprocations. When the bar 21, however, is forced downwardly the points or feeding ends of the fingers 22 move the lace downwardly and rearwardly along the lace table. 30 As shown in Figure 11, a tongue 28 is arranged centrally of the presser foot and spans the space between the two sections 15^a and 15^b thereof during the adjustment 35 thereof apart. The upper end of this tongue is mounted upon a pair of aligned pins 29 around which are placed a pair of light springs 30 whose function it is to hold the tongue 28 central with respect to the foot 40 when the parts of the foot are separated. The lace is fed along the upper and rear surface of this tongue 28 and beneath another tongue 31 hung at its upper end upon a pin 32 having its ends projecting into 45 spring sockets 33 spaced rearwardly from the pins 29. At 34 I show a pair of keepers extending downwardly along the edges of the tongue 31 and each having a finger 35 co-operating with the edge of the lace 50 close to one of the needles maintaining the lace in the position to which it is fed by the operation of the machine and the lace feeding fingers 22. These keepers 34 and their fingers 35 are carried substantially by 55 the side parts of the presser foot and hence always maintain substantially the same relation to the needles.

Referring now again to Figures 1 and 3, I show a pair of plungers 36 adapted to 60 reciprocate in vertical planes parallel to the line of feed along inclined guideways 37 at the side portions of the lace table, said guideways terminating at the bottom of the presser foot closely in front of the plane of 65 the needles. In the use of this machine the cloth between the two rows of stitches formed by the two needles is cut out by two pairs of cutting devices just ahead of the stitching mechanism, and the points of the plungers act between the spaces where the 70 cloth is cut and the plane of the needles. The round dull points 36' of the plungers are deflected inwardly and operate on their down stroke, just before the points of the needles reach the limit of their down stroke, 75 to hold the raw edges of the cloth turned downwardly in position to be turned beneath the salvage of the lace by the action of the thread as explained in detail in my Patent 80 #1,503,921. As shown in the first three 85 figures, the plungers are caused to reciprocate by means controlled directly from the needle bar. To this end I provide a rocker 38 journaled on a transverse axis 39, the ends of which are mounted in bearings or 90 brackets 40 carried laterally with the lateral adjustment of the two parts of the presser foot. The shaft 39 is telescopic at both ends so as to permit the rocker to remain central or in the vertical plane of the median 95 line of the work. The rocker includes upwardly and downwardly projecting arms 41 and 42 respectively, adapted to be engaged in alternation by the thimble 43 of the needle 100 holders. In the position shown in Figure 1, the needle bar may be regarded as descending and approaching its downward limit of movement, and immediately thereafter the thimble 43 or any analogous portion of the needle bar structure will engage 105 the arm 42 extending somewhat beneath the thimble and thereby the rocker will be given a quick oscillation rearwardly at its lower part. In other words, by the time the points 110 of the needles reach the cloth, the rocker will have been oscillated causing the points 36' of the plungers to be given their extreme downward throw. The connections between the rocker and the plungers are shown as comprising a pair of sleeves 44, in each of 115 which is a pin 45 adapted to project into the eye 46 of a draw bar 47 movable rearwardly in a horizontal plane due to the rearward oscillation of the rocker. The front end of each draw bar is deflected laterally 120 and projected through an inclined slot 48 formed in the upper end of the corresponding plunger 36. The plunger is held normally in its upper position by means of a light spring 49, and at this time the angular end of the draw bar occupies the lower 125 end of the slot 48. When, however, the draw bar 47 is drawn rearwardly by the oscillation of the rocker just described, since the draw bar is held in a horizontal plane by 130 the foot structure, the angular end thereof serves to draw the plunger downwardly along its inclined guideway. The pin 45 is held down in active position by a spring 50 housed within the sleeve 44, the spring bear-

ing against the angular upper end of the pin. If it is desired, however, to throw either or both of the pins out of connection with their draw bars, this may be effected 5 by lifting up upon the angular upper end of each pin, drawing the same upwardly against the spring 50, and then throwing the same laterally to lock in the bayonet slots 51 (see Figure 2). When the needle 10 bar moves upwardly, the thimble thereof is adapted to wipe against the upper arm 41 causing the rocker to oscillate in the other direction during the upper portion of such movement of the needle bar, setting the 15 plungers free to be lifted by the springs 49. The middle portions of the sleeves 44 are provided with rigid inwardly projecting aligned pin members 52 telescoping with the barrel 53 connected to the lower arm 42. 20 Either or both of the parts 39 and 53 may contain springs to hold the parts in proper relative positions upon lateral adjustment of the device. By the foregoing it will be seen that I have provided a means for actuating the cloth folding guides or plungers 25 downwardly and rearwardly, once for each downward reciprocation of the needles and just in advance of the needles. As shown in Figure 3, the pins 45 operate in 30 horizontal parallel slots 54 formed in the plates 54' along the upper edges of the bottom portions of the presser foot just in the rear of the side wings 26. By this means also the pins and sleeves are steadied with 35 respect to lateral vibrations.

In Figures 6 and 7 I show a slight variation in the cloth folding means. In this form of the device the plungers 36^a are relatively stationary when in operation, their 40 points 36' projecting normally below the ends of the guideways 37. Each plunger 36^a is pivotally connected at its upper end to a link 55 whose opposite end has a pivot pin 56 extending into a slot 66 of a latch 45. This latch is pivoted about its center upon a pivot 58 carried by a drop leaf 59 hinged at 60 near the bottom of the front portion of the presser foot. The pivot 58 projects through a longitudinal slot 61 at 50 the middle of the latch, and just above this slot and pivot is a lug 62. When the drop leaf 59 is closed flush with the front face of the presser foot, as shown in Figure 6, the upper end of the latch carrying a pin 55 projects into a socket 64 in the structure of the foot and substantially perpendicular to the drop leaf and link 55 lying against the upper face of the drop leaf at this time. A keeper 65 is slidable then 60 downwardly to engage at its lower end beneath the lug 62 thereby locking the drop leaf firmly in closed position, and the link causes the plunger point at this time to project into operative position. As shown in Figure 7, when the keeper 65 is ele-

vated or withdrawn from the latch lug 62, the operator by pulling directly downwardly upon the latch may swing the drop leaf 59 to its open position and by swinging the latch at its lower end rearwardly around 70 the pivot 58, the plunger and link will be drawn upward.

I will now describe the preferred cutting mechanism, having reference to Figures 3, 4 and 5, and also particularly to Figures 75 8 and 9. At 67 I show a cutting blade of peculiar construction adapted to reciprocate in a guideway 68 parallel to the plunger 26 or 36^a. This blade is provided at its lower rear end with a downwardly projecting lead 67', the point of which is intended as a guide rather than as a cutter. Just above and in front of the lead is provided a cutting edge 69, the line of which forms a comparatively sharp acute angle with the upper edge of the blade. This cutting edge 69 operates with a shearing effect with a stationary blade 70 fitted removably into a throat plate 71 (see Figure 5).

Adjacent to its upper end the blade is 90 formed with an open ended slot 72 substantially perpendicular to the longer axis of the blade and into which projects a pin 73 carried by a bell crank 74 pivoted at 75 on or within either half of the presser foot. 95 The upper or rear end of the bell crank 74 is bifurcated and intersects the slot 25 of the wing 26 for co-operating with the lug 24 carried by the positively actuated lace feeding bar 21. While the bar 21 is being elevated, the bell crank 74 is given a clockwise rotation (see Figure 4) causing the pin 73 to swing along an arc shaped slot 76, and through the connection at the slot 72 with the blade 67, the blade is driven downwardly and rearwardly, causing the cutting edge 69 thereof to shear across the active edge of the fixed blade 70 with a powerful and effective cut.

There is an intimate relationship between 110 the plunger mechanism and the cutting mechanism with respect to the latch 57. The extreme upper corner of the blade 67 is cut away, and a notch 77 is extended downwardly therefrom parallel to the slot 72. The pin 63 carried by the upper end of the latch is normally located in such position as to lie within the cut away corner portion of the blade, but away from the notch 77 (see Fig. 8). Therefore while the latch is 115 in locking position the blade is freed from the pin 63 for its reciprocations through the bell crank and pin 73, the plunger being held stationary by the latch and link connections. When, however, the latch is actuated to drop the drop leaf 59 to throw the plunger and knife out of gear, the first movement of the latch is longitudinal only as permitted by the slots 61 and 66 along 120 the pivots 58 and 56 respectively. This 125 130

- movement of the latch brings the pin 63 into the notch 77 whereby when the latch is then drawn downwardly and swung around the pivot 58, the blade will be drawn 6 positively downwardly to release it from the pin 73 and then drawn upwardly to bring the lead or point 67' thereof above the plane of the bottom of the presser foot (see Figure 9). In this position the device is adapted 10 for the sewing on of lace without cutting out the cloth, and with the blade dropped forwardly and downwardly, as shown, even though the bell crank may continue its oscillations, the pin 73 moves idly in the slot 76. 15 In the preferred form of the mechanism where the folding plungers are reciprocated in harmony with the reciprocations of the needle bar, it will be noted that when the needles are up and the feeding mechanism 20 is operative, the plungers likewise will be elevated, as shown in full lines in Figure 1, so that while the cloth is moving under the operation of the feeding devices there is practically no obstruction, tending to retard 25 or resist lateral curving of the work as contemplated in the practice of this entire machine.
- I will now describe the means I provide for adjusting the presser foot as to width, 30 according to the width of the lace. The presser foot bar includes or is provided with a downward projection 78 (see Figure 12) tapped transversely with screw threads having, for example, thirty-two threads per 35 inch co-operating with a screw 79 journaled in and held from endwise movement with respect to the foot part 15^a. To the outer end of the screw is connected a pinion 80 for controlling the rotation of the screw. If, 40 for instance, this screw be rotated eight times, the part 15^a will be moved laterally accordingly one-quarter of an inch with respect to the center or median line of the work. Another screw 81 is fixed rigidly in 45 the other part 15^b of the presser foot, and has internal threaded engagement with the first mentioned screw 79, but the threads of the screw 81 are made of twice the pitch of the first, or sixteen threads per inch. It 50 will be understood, however, that these pitches are but illustrations, and might be greater or less so long as the ratio of two to one is observed between the two parts of the differential pitch screw device. Since the 55 latter screw 81 is non-rotary, the rotation of the screw 79 and movement in one direction through a quarter of an inch with a corresponding unscrewing from the stationary screw 81, will cause the left hand part of the 60 foot to move in the opposite direction to the same extent. One or more other screws 81 are fixed to the foot part 15^b and are provided with similar threaded engagement with other rotary members 79' journaled in 65 the part 15^a. Each of these rotary shafts

79' is provided with a pinion 80 similar to the first one described. A master gear 82 is journaled so as to mesh with all of the pinions 80 and cause simultaneous rotation of all of them and the members 79 and 79', 70 whereby all parts of the foot are moved laterally bodily without wedging or cramping. A scale 83 is connected on the front portion of the foot to guide the operator in making the adjustment. 75

In Figures 13 and 14 I show my improved needle controlling device comprising a stationary bracket 84 connected by ears or lugs 85 to any stationary part of the head. A differential screw 79^a and 81^a of the same character as I described in connection with the presser foot, is connected to the bracket 84. The end of the screw carrying the pinion 80 is journaled in a laterally adjustable bracket extension 86 having a socket 87 for 80 a needle chuck 88, to which the needle is connected for vertical reciprocations. The non-rotary screw 81^a is carried by another laterally adjustable extension 89. The differential screw just described is actuated preferably by the same master wheel and at the same time that the adjustment of the presser foot is effected and to the same extent. The front face of the bracket mechanism may be 85 provided with a scale 90 to guide the operator in making the adjustment, either independently of or in connection with the scale 83 on the presser foot. 90

The lower end of the needle bar 20 which reciprocates through the center of the bracket 84 carries a pair of needle holders 91 and 92 in which the needle chucks 88 are held during the operation of the needles with the needle bar. These holders 91 and 92 are adapted to be clamped as by means of a binding screw 93 at the center to hold them in fixed position with respect to the needle bar. When the bracket device 84 is to be adjusted laterally or elongated, the screw 93 will be loosened and then the upper ends of 100 the chucks which project into the bracket extensions 86 and 89 will be carried apart bodily, providing the same adjustment laterally for the needles as is given to the presser foot and other devices described, so that the 105 needles will reciprocate along the same vertical lines with respect to the presser foot. At each side of the device I provide a finger piece 94 in the nature of a bell crank, which 110 when swung downwardly by the operator, will cause a dog to swing inwardly to catch and hold the chuck in the bracket extension and release it from the needle holder 91 or 92. This operation as described in the 115 previously mentioned application may be performed easily and safely while the machine is in regular operation. If it is desired to stop either or both needles while the machine 120 is in operation, to start the needle or needles that may be stopped, the operator will sim- 125

ply throw the finger piece 94 back to the original position and the needle chuck will then be carried downwardly as usual by the needle holder and needle bar.

5 I claim:

1. In a two needle lace sewing machine, the combination with a presser foot, a pair of needles co-operating therewith, and cloth cutting means adjacent to each needle, of laterally spaced cloth folding devices co-operating with the presser foot between the needles and the cutting devices.

10 2. In a two needle lace sewing machine, the combination with a presser foot, a pair of reciprocating needles co-operating therewith, and cloth cutting devices acting in front of the needles, of a pair of cloth folding plungers movable downwardly into co-operation with the presser foot between the needles and the cutting devices.

15 3. In a lace sewing machine, the combination with a presser foot, a pair of needles co-operating therewith, means to reciprocate the needles, laterally spaced cutting devices slitting the cloth ahead of the needles, a pair of plungers co-operating with the raw edges of the cloth to fold the same, and means to reciprocate the plungers from the needle operating means in harmony with the reciprocations of the needles.

20 4. The combination with a presser foot, a needle co-operating therewith, lace feeding means acting downwardly through the front portion of the foot, and slitting devices acting on the cloth in front of the lace, of a plunger guided for reciprocating movement adjacent to the front part of the foot, and means to reciprocate the plunger coincidentally with the needle mechanism, the plunger serving to fold the cloth beneath the selvage of the lace and acting just ahead of the down stroke of the needle point.

25 5. In a lace sewing machine, the combination with a presser foot, a needle bar and needle reciprocating with respect thereto, and cloth cutting means acting in front of the needle, of a cloth folding plunger reciprocating along an inclined guideway at the front part of the presser foot toward and from the axis of the needle, a draw bar connected to the plunger, and means actuated by the needle bar to cause the reciprocating of the draw bar in a horizontal plane to cause the downward movement of the plunger when the needle bar moves downwardly.

30 6. In a two needle lace sewing machine, the combination of a presser foot, a needle bar, a pair of needles carried by the needle bar, means to feed laces beneath the needles, cutting devices to trim the cloth between the lines of action of the needles, and a pair of raw edge folding members acting to hold the raw edges of the cloth downward with respect to the needles, and a member actuated

35 by the needle bar on its down stroke to cause the operation of the cloth folding devices.

7. The herein described presser foot having in its front portion a pair of parallel downwardly and rearwardly inclined guideways, a cloth cutting member reciprocating in one of the guideways, a cloth folding member reciprocating in the other guideway, a needle between the axis of which and the cutting member the folding member is caused to operate, and means to positively reciprocate the cutting member and the folding member.

40 8. In a lace sewing machine, the combination of a presser foot, a cutting member and a cloth folding member reciprocating parallel to each other in the front portion of the foot along diagonal lines with respect to the axis of the needle, and means to reciprocate the cutting member and the folding member one after the other.

45 9. In a two needle lace sewing machine, the combination of a presser foot, means to feed lace downwardly and rearwardly along the front portion thereof, a pair of needles, means to reciprocate the needles through the lace and cloth at the middle portion of the foot, a cutting member and a cloth folding member acting in succession upon the cloth adjacent the line of action of each needle, means to operate the cloth cutting members, and means actuated by the needle mechanism to actuate the cloth folding members simultaneously, forcing them downwardly while the needles are making their down stroke, and holding the folding members down until the needles start upon their up stroke.

50 10. The combination with a presser foot, a needle bar, and a needle carried thereby reciprocating with respect to the presser foot, of a cloth cutting device movable downwardly and rearwardly toward the axis of the needle, a folding member acting upon the cloth, and a member actuated by the needle bar on its down stroke to cause a corresponding actuation of the member acting upon the cloth.

55 11. A sewing machine having a plurality of needles adapted to have their distance from each other varied, a separate cloth cutting device for each needle, and means whereby the lateral adjustment of a needle will produce a simultaneous lateral adjustment of its cloth-cutting device.

60 12. In a two needle lace sewing machine, the combination of a presser foot having guideways formed in its front portion, a plurality of members movable in said guideways to act upon the cloth, a rocker journaled upon the presser foot, a reciprocating needle bar, a portion of the rocker being in position to be actuated by the needle bar during its reciprocations, and connections between said cloth actuating members and

the rocker whereby the oscillation of the rocker will cause simultaneous movement of the members acting upon the cloth.

13. The combination with a presser foot having a downwardly and rearwardly inclined guideway in its front portion, a needle bar, and a needle reciprocating vertically with respect to the foot, of a member acting upon the cloth in front of the needle and mounted for movement in said guideway, a forwardly and rearwardly reciprocating draw bar having its front end connected to the member acting on the cloth, a rocker journaled on a transverse axis upon the presser foot in position to be actuated by the needle bar, and connections between the rocker and said draw bar to cause the movement of the member acting on the cloth according to the movement of the needle bar.

14. A sewing machine having a plurality of needles adapted to have their distance from each other varied, a presser foot having a separate section for each needle, said sections being relatively adjustable laterally, a separate cloth-cutter carried by each of said sections, and means whereby the lateral adjustment of a presser foot section will produce a simultaneously lateral adjustment of the corresponding needle and cloth-cutter.

15. In a two needle sewing machine, the combination with a presser foot divided centrally, the division line being longitudinal of the direction of feed, a pair of needles respectively connected to the two parts of said presser foot, and means to reciprocate the needles in cooperation with the presser foot, of means to feed lace along the presser foot beneath the needles, and means to adjust the two parts of the presser foot and the needles laterally toward and from each other, and equally relatively to the longitudinal central division line of said presser foot.

16. In a two needle lace sewing machine, the combination with a pair of needles and means to reciprocate the same, of a presser foot co-operating with the needles and divided along a vertical plane coinciding with the median line of the work, means to feed lace along the front portion of the presser foot beneath the needles, the lace feeding means being also divided in the same plane as the presser foot, and means to widen the presser foot and the lace feeding means simultaneously to accommodate wider lace.

17. In a two needle lace sewing machine, the combination with a pair of needles and means to reciprocate the same, of a presser foot divided along a central vertical plane coinciding with the median line of the work, means to feed lace along the front part of the presser foot beneath the needles, said lace feeding means also being divided along the same plane as the presser foot, and ro-

tary means acting simultaneously upon both the presser foot and the lace feeding means to cause the widening of the same simultaneously and to the same extent to accommodate wider lace.

18. In a two needle lace sewing machine, the combination with a pair of needles and means to reciprocate the same in a vertical transverse plane, of a presser foot divided in a vertical plane perpendicular to the plane of the needles, said presser foot being formed with a transverse slot coincident with the plane of the needles and along the ends of which the needles are adapted to reciprocate, means to feed lace downwardly through said slot beneath the needles so that the edges of the lace are engaged by the needles, and means to widen the presser foot to elongate the slot, to widen the lace feeding means, and to adjust the needles farther apart to correspond to the widening of the presser foot and lace feeding means.

19. In a two needle lace sewing machine, the combination with a pair of needles and means to reciprocate the same in a vertical transverse plane, of a presser foot having a transverse slot coinciding with said plane, means to feed lace through the slot beneath the needles, the edges of the lace moving along the ends of the slot and engageable by the needles, means to adjust the lace feeding means to accommodate wider lace, means to increase the effective length of the slot accordingly, and means to widen the space between the needles so that the points of the needles always pass through the edges of the lace irrespective of the width thereof.

20. In a two needle lace sewing machine, the combination of a presser foot having a transverse slot, means to feed lace downwardly through the slot with the edges thereof passing along the ends of the slot, a pair of needles, means to reciprocate the needles causing the points thereof to pass through the edges of the lace close to the ends of the slot, and means to increase the effective length of the slot to accommodate wider lace.

21. In a lace sewing machine, the combination of a presser foot comprising two relatively laterally movable parts, means to feed lace along the front part of the presser foot, said lace feeding means including a pair of tongues spanning the gap between the parts of the presser foot, and between which tongues the lace is caused to move; means to hold the lace in the position to which it is fed, and stitch forming means co-operating with the lace at the bottom of the presser foot.

22. In a lace sewing machine, the combination of a presser foot comprising two laterally movable parts, means to adjust said parts toward and from each other according to the width of the lace, a tongue connected to the front part of the presser foot and ex-

5 tending rearwardly and spanning the gap between the two parts of the foot, and over which tongue the lace is fed, a vertically reciprocating lace feed bar acting above the lower portion of the tongue, a series of lace engaging fingers moved downwardly and rearwardly by operation of said vertically reciprocating feed bar, means acting upon the lace to hold it in position to which it is 10 fed, and stitch forming mechanism acting upon the lace at the bottom of the presser foot.

23. In a lace sewing machine, the combination of a presser foot comprising two parts 15 movable laterally toward and from each other, the foot being provided with a transverse slot extending into both parts, the length of the slot increasing with the movement of the parts of the foot away from 20 each other, means to feed lace through said slot, the lace feeding means comprising relatively movable parts to accommodate different widths of lace, a pair of needles, means to reciprocate the needles through the ends 25 of the slot and edges of the lace, and means to adjust the needles apart and simultaneously widen the presser foot and lace feeding devices, said adjusting means including a series of compound screws, a series of pinions connected to the ends of the screws, and 30 a master gear meshing with all of said pinions.

24. In a sewing machine, a presser foot having a guide-way, and a cloth-cutter arranged to reciprocate in a vertical plane along said guideway, the cutting edge of said cutter and the direction of movement thereof, being diagonal to the direction of feed of the cloth.

40 25. In a lace sewing machine, the combination with a presser foot, a reciprocating needle bar and needle cooperating therewith, and cloth cutting means acting in front of the needle, of a folding device movable in a 45 vertical plane for folding the raw edge of the cloth and acting thereon between the cutting means and the needle, and means to actuate the folding device simultaneously with the needle bar.

50 26. In a lace sewing machine, the combination with a presser foot, a needle bar, and a needle co-operating therewith, of a cloth cutting device acting to slit the cloth in front of the needle, lace feeding means disposed above the bed plate of the machine and directed toward the needle, means directly connecting said lace feeding means and the cutting device to actuate the lace feeding means and the cutting device one 55 ce from the other, and a folder for the raw edge of the cloth between the cutting device and the point of application of the lace to the cloth.

60 27. In a lace sewing machine, the combination with a presser foot, a needle bar

co-operating therewith, and a needle carried by the needle bar, of a lace feeding bar disposed above the bed plate of the machine, and reciprocating along the front part of the presser foot toward the needle, a reciprocating cloth cutting blade in front of the needle and point of application of the lace to the cloth, means directly connecting said lace feeding means and the blade, to actuate the blade from the lace feeding bar in opposite 75 directions, and a folder for the raw edge of the cloth between the blade and the point where the lace is stitched to the cloth.

28. In a lace sewing machine, the combination with a presser foot and stitch forming mechanism, co-operating therewith, of a lace feeding bar disposed above the bed of the machine and reciprocating with respect to the front part of the presser foot along a certain transverse plane, a cloth 80 cutting blade movable along the presser foot in a plane in front of and at an angle to the plane of the feeding bar, and a bell crank connection directly connecting said lace feeding bar and said cutting blade to actuate the cutting blade from the feeding bar.

29. In a lace sewing machine, the combination of a presser foot having a transverse slot in its bottom, means disposed above the bed plate of the machine to feed lace downwardly through said slot and including a reciprocating bar, means to stitch the lace to the cloth beneath the slot, a cloth cutting blade guided for reciprocation in the front part of the presser foot, a lever pivoted on 100 the presser foot between the lace feeding bar and the blade, and direct pivotal connections between the ends of the lever and the bar and blade respectively whereby the blade is actuated from the bar, but in an 105 opposite direction.

30. In a two needle lace sewing machine, the combination of a presser foot having a transverse slot in its bottom, a pair of transversely adjustable needles acting through 110 said slot, means to feed lace downwardly and rearwardly through said slot beneath the needles, cutting means to trim the cloth between the rows of stitches formed by the needles, and means acting between the cutting means and the needles to turn the raw edges of the cloth downward so as to be engaged by said stitches.

31. In a lace sewing machine, the combination of a presser foot having a pair of 120 parallel inclined guideways in its front portion, a cloth folding member located in one of said guideways, a cloth cutting member in the other guideway, means to reciprocate the cutting member along its guideway, and stitch forming mechanism acting upon the cut and folded cloth in the rear of the cutting and folding members.

32. The combination of a presser foot, means to feed lace downwardly and rear-

wardly along the front portion thereof, a pair of needles, means to reciprocate the needles through the lace and cloth at the middle portion of the foot, cloth cutting members acting on the cloth respectively in front of each needle, means to operate the cloth cutting members, and means acting between the cutting members and the needles to cause the raw edges of the cloth to fold beneath the edges of the lace.

33. The combination with a presser foot, a needle bar, and a needle carried by the needle bar, of means to trim and fold the cloth in front of the needle, a member pivoted upon a horizontal pivot upon the presser foot adjacent to the needle bar and operated thereby, and connections between the pivoted member and the folding means to actuate the latter coincidentally with the downward movement of the needle bar.

34. In a two needle lace sewing machine, the combination of a presser foot having guideways in its front portion, reciprocating needle mechanism co-operating with the presser foot, a member pivoted upon the presser foot in position to be oscillated by the needle mechanism during the reciprocations thereof, a plurality of cloth cutting and folding members movable in said guideways, and connections between the pivoted member and the folding members whereby the oscillation of the pivoted member will cause the active operation of the folding members coincidentally with the downward reciprocation of the needle mechanism.

35. In a lace sewing machine, the combination of a presser foot comprising two relatively laterally movable parts, means to feed lace to and through the presser foot, said feeding means including devices spanning the gap between the parts of the presser foot and along which spanning devices the lace is caused to move, means to hold the lace in the position to which it is moved, and stitch forming means co-operating with the edges of the lace at the bottom of the presser foot.

36. In a two needle lace sewing machine, the combination of a two-part variable width presser foot, a rocker pivoted upon the two parts of the presser foot, means to hold the rocker in substantially the same position irrespective of the variation in width of the presser foot, reciprocating needle mechanism including a thimble co-operating with the rocker to move the same around its pivot, means acting upon the cloth in front of the needle mechanism and below the presser foot, and draw bar connections between the last mentioned means and the rocker whereby the means acting upon the cloth are caused to act coincidentally with the reciprocation of the needle mechanism.

37. In a lace sewing machine, the combination of a presser foot, a rocker pivoted

upon the presser foot on a horizontal pivot and including a downwardly projecting blade, a needle bar adapted to engage said blade on its down stroke and cause the oscillation of the rocker, a sleeve extending downwardly from the rocker at one side of the blade, means acting upon the cloth beneath the front part of the presser foot, a horizontal draw bar attached at one end to the means acting upon the cloth, the other end of the draw bar having an eye, and a pin extending from the lower end of the sleeve into said eye for actuation of the draw bar from the needle bar and rocker.

38. In a lace sewing machine, the combination of a presser foot, a needle bar, a rocker pivoted upon the presser foot and having a projecting blade adapted to be engaged by the needle bar to oscillate the rocker, a sleeve projecting downwardly from the rocker, a pin slideable longitudinally in the free end of the sleeve and projecting normally therefrom, a cloth folding plunger guided for reciprocation in the front part of the presser foot, a member connecting the pin aforesaid with said plunger, means to hold the pin retracted into the sleeve when the plunger is to be idle, and means connected to the plunger to hold it up in idle position when the pin is retracted from said connecting member.

39. In a lace sewing machine, the combination of a presser foot, a reciprocating needle bar, a rocker mounted upon the presser foot adjacent to the needle bar and adapted to oscillate around a horizontal pivot, a pair of blades carried by the rocker and extending at an angle to each other above and below said pivot and engageable in alternation by the needle bar as it approaches the ends of its reciprocations whereby the rocker is actuated positively in both directions, means acting upon the cloth in front of the needle bar, and connections between the last named means and said rocker.

40. In variable width presser foot mechanism for sewing machines, the combination with the relatively laterally adjustable parts of the foot, of a compound differential pitch screw extending between said two parts, the presser foot having a stationary projection between the adjustable parts, one part of the screw being journaled in one presser foot part and threaded into said projection, and another part of the screw being fixed to the opposite foot part and having threaded engagement with the journaled part of the screw, the two sets of threads being of different pitch, and means to rotate the one screw part whereby both foot parts are actuated simultaneously in opposite directions.

41. In a variable width two needle lace sewing machine, the combination of a two part presser foot, a plurality of compound

- 5 screws extending between the two parts of the foot, one part of each screw being journaled in one foot part but held from endwise movement with respect thereto, the other part of the same screw being fixed to the opposite foot part, and means to rotate all the journaled screw parts simultaneously whereby the foot parts are moved in opposite directions in parallelism.
- 10 42. In a sewing machine, a presser foot having a rearwardly inclined guideway, and a cloth cutter arranged to reciprocate along said guideway, the cutting edge of said cutter and the direction of movement thereof, being diagonal to the direction of feed of the cloth.
- 15 43. In a sewing machine, a presser foot, and a cloth-cutter carried by said presser foot and movable thereon, the cutting edge of said cutter and the direction of movement thereof, being diagonal to the direction of feed of the cloth.
- 20 44. In a sewing machine, a pressure foot, and a cloth-cutter carried by said presser foot and movable thereon in a plane extending lengthwise of the line of feed, the cutting edge of said cutter and the direction of movement thereof, being diagonal to the direction of feed of the cloth.
- 25 45. In a sewing machine, a presser foot, and a cloth-cutter carried by said presser foot and movable thereon in a plane extending lengthwise of the line of feed in an inclined path, the cutting edge of said cutter and the direction of movement thereof, being diagonal to the direction of feed of the cloth.
- 30 46. In a sewing machine, a presser foot provided with a guideway inclined downwardly and rearwardly in a vertical plane parallel to the line of feed, and a cloth-cutter arranged to reciprocate along said guideway, the cutting edge of said cutter and the direction of movement thereof, being diagonal to the direction of feed of the cloth.
- 35 47. In a sewing machine, a presser foot having apertures for the passage of two needles, and two cloth-cutters carried by said presser foot movably and arranged to operate between the planes in which the said needles operate.
- 40 48. In a sewing machine, two adjacent reciprocating needles arranged laterally of each other with respect to the line of feed, a presser foot, and two cloth-cutters carried by said presser foot movably and spaced laterally from each other a distance smaller than the lateral spacing of the needles, said cloth-cutters operating between the lines of operation of the two adjacent needles.
- 45 49. In a sewing machine, a reciprocating needle-carrying bar, a presser foot co-operating with the needle, means for folding lace relatively to said presser foot, a cloth-
- 5 folder carried by the presser foot and movable relatively thereto, and means for actuating said cloth-folder by the movement of the needle bar.
- 50 In a sewing machine, a presser foot 70 consisting of sections both relatively adjustable to vary the distance between them, said sections adapted to contact with each other in the extreme narrow position of said presser foot, and a tongue extending over the upper surfaces of said sections to span the space between said sections when they are separated.
- 55 51. In a sewing machine, a presser foot comprising sections relatively adjustable in a direction, transverse to the line of feed, a tongue to span the space between said sections, and a lace feeder movable in co-operation with said presser foot sections and tongue.
- 56 52. In a sewing machine, a presser foot comprising sections relatively adjustable in a direction transverse to the line of feed, a tongue to span the space between said sections, and a lace feeder movable in co-operation with said presser foot sections and tongue, and comprising sections associated with the respective presser foot sections and adjustable relatively in a transverse direction.
- 60 53. In a sewing machine, a presser foot comprising sections relatively adjustable in a direction transverse to the line of feed, and a lace-feeder movable relatively to the presser foot to co-operate therewith, and comprising sections adjustable relatively in a transverse direction and associated with the respective presser foot sections.
- 65 54. In a sewing machine, a presser foot comprising sections relatively adjustable in a direction, transverse to the line of feed, and means for effecting the relative adjustment of said sections, said means including a plurality of screws connecting said sections, pinions on the said screws, and a master gear meshing with said pinions to operate them together.
- 70 55. In a sewing machine, a presser foot comprising sections relatively adjustable in a direction, transverse to the line of feed, reciprocating needle-holders likewise relatively adjustable in a transverse direction, a plurality of adjusting screws connecting the needle-holders, a plurality of adjusting screws connecting the presser foot sections, pinions on all of said screws, and a master gear meshing with all of said pinions to effect simultaneously a relative adjustment of the needle-holders and of the presser foot sections.
- 75 56. In a lace sewing machine, a presser foot, means for feeding lace relative to said presser foot, and a cloth-folder movable on said presser foot in a plane extending lengthwise of the line of feed.

57. In a lace sewing machine, a presser foot, means for feeding lace relative to said presser foot, and a cloth-folder movable on said presser foot in a vertical plane extending lengthwise of the line of feed.
58. In a lace sewing machine, a presser foot, means for feeding lace relative to said presser foot, and a cloth-folder movable on said presser foot, lengthwise of the line of feed and obliquely to such line.
59. In a lace sewing machine, a presser foot, means for feeding lace relative to said presser foot, stitching mechanism, and a cloth-folder movable in front of said mechanism in a plane extending lengthwise of the line of feed.
60. In a lace sewing machine, stitching mechanism, a presser foot, means for feeding lace relative to said presser foot, and a cloth-folder movable in front of said mechanism in a vertical plane extending lengthwise of the line of feed.
61. In a lace sewing machine, stitching mechanism, a presser foot, means for feeding lace relative to said presser foot, and a cloth-folder movable in front of said mechanism lengthwise of the line of feed and obliquely thereto.
62. In a sewing machine, two adjacent and spaced needles disposed in a line transverse to the line of feed of the material, and two spaced cloth cutters arranged to operate in front of the needles to form two cuts in the material between the lines of operation of the needles to cut a portion of material therefrom.
63. In a sewing machine, two adjacent and spaced needles disposed in a line transverse to the line of feed of the material, and two spaced cloth cutters arranged to operate in front of the needles to form two cuts in the material between the lines of operation of the needles to cut a portion of material therefrom, and means for supplying lace to bridge the opening which results from the operation of said cutters.
64. In a sewing machine, a cloth cutter having up and down movement in a straight line and provided with an oblique cutting edge adapted to cut into the cloth as said cutter descends with a uniform cutting force, the cutting point of engagement moving downwardly and rearwardly as the cutter descends.
65. In a sewing machine, a presser foot consisting of normally contiguous sections relatively adjustable to vary the distance between them, and means extending at its side edges over the upper surfaces of said sections and adapted to span the space between said sections when separated.
66. In a lace sewing machine, the combination of a presser foot comprising two relatively laterally movable parts, means to feed lace to and through the presser foot, said feeding means including devices spanning the gap between the parts of the presser foot and along which spanning devices the lace is caused to move.
67. In a sewing machine, a presser foot consisting of a pair of sections relatively adjustable to vary the distance between them, a lace guiding tongue to span the space between said sections, and spring means disposed between said tongue and said sections to maintain said tongue centrally of the side extremities of said sections.
68. In a sewing machine, a presser foot consisting of a pair of sections relatively adjustable to vary the distance between them, a lace guiding tongue to span the space between said sections, means disposed between said tongue and said sections to maintain said tongue centrally of the side extremities of said sections, a keeper disposed over said tongue and spring means disposed between said keeper and said sections to maintain said keeper centrally of the side extremities of said sections.
69. In a sewing machine, a presser foot consisting of a pair of sections relatively adjustable to vary the distance between them, a tongue to span the space between said sections, and means carried by said sections and adapted to span the space between said tongue and the side extremities of said sections.
70. In a sewing machine, a presser foot consisting of a pair of sections relatively adjustable in a direction transverse to the line of feed, reciprocating needle holders provided with needles likewise relatively adjustable transversely to the line of feed, lace guide means carried by said presser foot, and keepers on said respective sections movable therewith and provided with fingers adapted to maintain a constant position relatively to said needles.
71. In an adjustable two-needle sewing machine, a bar, a presser foot comprising a pair of sections extending on opposite sides of the bar and having needle openings, and means for adjusting the sections simultaneously and equally toward or from the bar, said means comprising a screw rotatably mounted in one of said sections and threaded into the bar and a second screw fixed in the other section and secured to the first-mentioned screw by threads having twice the pitch of the threads on the first-mentioned screw.

RALPH M. SHARAF.
